ROLLER SKATE

Daniel S. Williams, 394 Spruce St., Pottstown, Pa.
Filed Nov. 22, 1960, Ser. No. 70,950
3 Claims. (Cl. 280—11.26)

This invention relates to a roller skate, and more particularly to a roller skate having an improved mechanism for permitting adjustment between the heel member and sole member so that the roller skate can be readily and conveniently adjusted to the desired length as desired or required.

The primary object of this invention is to provide a roller skate which is adapted to be made of strong light weight plastic material and wherein the roller skate is especially suitable for use by young children since the roller skate of the present invention embodies a novel adjusting mechanism which permits the child to readily adjust the skate to the desired length without requiring the use of any special wrench or the like, or without requiring assistance from an adult or other person.

A further object of the invention is to provide a roller skate which includes a safety back brake which will help prevent the child using the skates from falling backwards, forward or turning the ankle, and wherein the skates of the present invention include a unique adjustable locking mechanism that permits the user such as a small child to position the heel and toe members at the proper location, and wherein after the parts have been adjusted to the desired location, they will remain in that location or position until the child desires to again adjust the length of the roller skates.

Still another object is to provide such roller skates that are economical to manufacture and efficient in operation and which are rugged in structure and foolproof in use.

These and other objects of the invention will become apparent from a reading of the following specification and claims, taken with the accompanying drawings, wherein like parts are referred to and indicated by like reference characters and wherein:

FIGURE 1 is a top plan view illustrating a roller skate constructed according to the present invention.

FIGURE 2 is a sectional view taken on the line 2—2 of FIGURE 1.

FIGURE 3 is a bottom plan view of the roller skate of the present invention, with parts broken away and in section.

FIGURE 4 is a sectional view taken on the lines 4—4 of FIGURE 2.

FIGURE 5 is a view generally similar to FIGURE 4 but showing the parts in a different or adjusted position.

FIGURE 6 is a fragmentary perspective view showing a portion of the shank with the external threads or ribs thereon.

FIGURE 7 is a fragmentary perspective view showing a portion of the barrel or tube.

FIGURE 8 is a transverse sectional view illustrating the locking mechanism of the present invention and showing the tube with the shank therein and illustrating the parts in unlocked position so that relative movement between the tube and shank can take place.

FIGURE 9 is a view similar to FIGURE 8 but showing the parts in locked position.

FIGURE 10 is a sectional view taken on the line 10—10 of FIGURE 2.

FIGURE 11 is a sectional view taken on the line 11—11 of FIGURE 2.

FIGURE 12 is a sectional view generally similar to FIGURES 8 and 9, but illustrating a modification.

Referring in detail to the drawings, and more particularly to FIGURES 1 through 11 of the drawings, there is illustrated a roller skate which is especially suitable for

2

use by small or young children learning to skate, and wherein the skate can be used indoors or outdoors, and the various parts of the skate are adapted to be made of a suitable material such as a tough colorful plastic of a suitable composition. One of the skates is indicated generally by the numeral 30, FIGURE 1, and it is to be understood that a pair of the skates 30 are adapted to be used and each has the same construction and each includes a heel member 31 as well as a sole member or toe member 32. The heel member 31 is shaped to include a horizontally disposed base portion 33, FIGURE 2, and depending from the base portion 33 and secured thereto or formed integral therewith is a generally V-shaped cradle 34 which has a rear axle 35 extending through the lower portion thereof. A pair of rear wheels 36 are mounted on the outer ends of the axle 35 as shown in the drawings.

The skate 30 further includes a flanged section which is indicated generally by the numeral 37, and the flanged section 37 depends from the base portion of the heel member and as shown in the drawings the flanged section 37 has its lower edge as indicated by the numeral 38 normally spaced above a surface such as a floor surface 39 whereby the flanged section will provide a safety feature that will help prevent a child from falling backwards, forward, turning an ankle or the like. The flanged section 37 is shaped to include spaced apart side portions 40 which are cut away as at 42 so as to provide clearance for the wheels 36, and the flanged section 37 also includes a rear portion 43 which is provided with an arcuate recess 44.

Extending upwardly from the base portion 33 and affixed thereto or formed integral therewith is a pair of spaced apart apertured brackets 45, and the numeral 46 indicates a strap which may be made of a suitable flexible plastic material. The retaining strap 46 is provided with a plurality of notches or teeth 47 on one end portion thereof, while the other end of the strap 46 is provided with slots or openings 48 and 49 for receiving the toothed portion 47 so that the strap can be maintained in its proper position on the child's ankle or foot.

The side portions 40 are further provided with upper skirt portions 41 which are arranged in a generally raised position above the rear wheels 36.

The heel member 31 further includes a vertically disposed end portion 50, FIGURE 10, and the end portion 50 is shaped to include an intermediate enlarged rounded section 51 as well as upper portions 52 of reduced size. Vertically disposed spaced parallel brace pieces 53 extend between the rounded section 51 and the cradle 34 and are secured thereto or formed integral therewith so as to help maintain the parts in their proper spaced position or location. There are also provided inclined or angularly arranged brace members 54 which extend between the brace pieces 53 and the skirt portions 41 and which are secured thereto, and the numeral 55 designates each of a pair of spaced parallel vertically disposed brace elements which are secured between the brace members 54 and the enlarged rounded section 51 of the end portion 50 whereby a rugged construction is provided that provides support for the various parts such as the horizontally disposed hollow tubular shank 56. The shank 56 forms part of an adjustable locking mechanism that is indicated generally by the numeral 57, and the locking mechanism 57 further includes a hollow tube or barrel 58 as later described in this application. As shown in FIGURE 6 for example the shank 56 includes two groups or sets of threads or ribs and each group of ribs is indicated generally by the numeral 59 and it will be seen that each group 59 embodies a plurality of spaced parallel arcuate ribs 60 which distend an arc of approximately 180°. The ribs 60 are adapted to be provided with slight-

ly flattened outer edges or surfaces as indicated by the numeral 61, and each pair of adjacent or continuous ribs 60 defines therebetween a groove 62. The shank 56 is further provided with a pair of diametrically opposed longitudinally extending channels or recesses 63, and the pair of groups of ribs 59 are separated by the pair of channels 63.

The shank 56 further includes an end portion 64 which is smooth and free of threads or ribs.

As shown in the drawings the sole member 32 is shaped to include a horizontally disposed base piece 65 which is provided with an upstanding generally closed toe piece 66 adjacent the front thereof, and depending from the base piece 65 is a pair of spaced parallel vertically disposed side members 67, each of the side members 67 being shaped to include a generally triangularly shaped section 68. The triangularly shaped sections 68 are joined at their lower surfaces by an arcuate cross-piece 69, and the numeral 70 indicates a front axle which extends between the side sections 68 and the axle 70 has a pair of front wheels 71 mounted thereon.

One end of the shank 56 is secured to or formed integral with the rounded section 51 of the end portion 50, and the shank 56 is adapted to telescope into the hollow tube 58, and the tube 58 is fixedly mounted to the lower surface of the base piece 65, the tube 58 being hollow and having its end open whereby the shank 56 can be adjustably and rotatably received therein.

The crosspiece 69 is also secured to the lower end portion of the tube 58 or formed integral therewith so as to help brace and support the tube 58, and the numeral 72 indicates a horizontally disposed brace which extends between the side sections 68, and the brace 72 is also secured to the lower portion of the tube 58 whereby the tube will be properly supported and maintained in the desired location. Diametrically opposed brace arms 73 extend between the inner surfaces of the side sections 68 and the outer surface of the tube 58 as shown in FIGURE 11 in order to further strengthen and brace the adjacent elements.

The tube 58 is provided with a pair of inwardly directed or inwardly disposed diametrically opposed tongues or protuberances 74, FIGURE 7.

As shown in the drawings the tube 58 is provided with inwardly disposed thickened shoulders or portions 75 which have opposed flat surfaces 76 for coaction with the flat surfaces 61 of the ribs 60 so that these coacting flat surfaces 61 and 76 will provide a slight camming or wedging action in order to help prevent accidental rotation or shifting of the shank and tube relative to each other from their adjusted position. However, this wedging action can be overcome by applying manual pressure to the members 31 and 32 so that the effective length of the roller skate can be adjusted as desired by the child.

Referring now to FIGURE 12 of the drawings there is illustrated a slight modification of the adjustable locking mechanism which is indicated generally by the numeral 57', and it will be seen that the locking mechanism 57' has generally the same construction and operation as the previously described locking mechanism 57. However, the locking mechanism 57' includes a shank 56' which is provided with diametrically opposed longitudinally extending channels 63' for at times receiving the tongues 74 of the tube 58 as for example when the length of the roller skate is to be adjusted, and in addition, the shank 56' includes two groups of arcuate spaced parallel ribs 59' which are separated from each other as at 77, and as shown in FIGURE 12 the ribs 59' only extend through an arc of approximately slightly less than 90°, whereas the ribs 60 shown in FIGURE 6 extend through an arc of approximately 180°.

From the foregoing, it is apparent that there has been provided roller skates which are especially suitable for use by small children learning to skate, and wherein substantially all of the parts of the roller skates are adapted

to be made of tough unbreakable plastic material and the skates are appealing in appearance and also incorporate or embody certain functional features which are believed to be advantageous. The skates can be used indoors or outdoors and are strong and light in weight and the skates include the flanged section 37 which has its lower edge 38 arranged just above the floor surface or other surface 39 on which the skates are being used so that the flanged section 37 will function as a safety factor or safety back brake whereby in the event the child or user starts to fall backwards or to the side, the edge 38 will move into engagement with the floor surface 39 in order to help maintain the child upright.

The skate includes the sole member 32 which is provided with generally closed toe piece 66 that is secured to or formed integral with the base piece 65, and the piece 66 is adapted to snugly receive therein the toe portion of the child's shoe or foot, and as shown in the drawings, there is provided on the rear intermediate portion of the toe piece 66 a generally circular enlargement 78. This projection or portion 78 helps guide the child's shoe or foot into the toe portion 66 and exerts a wedging action so that the skate can be worn more comfortably and with less likelihood of accidental disengagement of the shoe from the skate. As shown in the drawings the rear portion of the toe piece 66 is open so that the child's shoe can fit therein, and the entire front of the toe piece is closed.

The skate includes the novel locking mechanism which is indicated generally by the numeral 57 so that the child using the skates can readily adjust the skates to the desired or required length without requiring any special pull or without requiring outside assistance and the locking mechanism is constructed in such a manner that after it has been adjusted it will have a tendency to remain stationary in the desired position. The locking mechanism embodies the shank 56 which is secured to or formed integral with the rounded section 51 on the end of the heel member 31, and this shank 56 is of a diameter so that it can swivel and move longitudinally within the hollow tube 58, the tube 58 being fixedly secured to the sole member 32. The shank 56 includes the two groups of ribs or threads 59 which each embody the spaced parallel arcuate rib members 60, and the rib members 60 are spaced from each other so as to provide grooves 62 therebetween, and there are also provided the longitudinally extending channels 63. The shank 56 includes the smooth portion 64 which is free of ribs and this smooth portion helps provide a guiding element as for example when initially inserting the shank into tube 58.

When the length of the skates is being changed or adjusted, the parts are arranged so that the pair of channels 63 are in alignment or registry with the pair of inwardly disposed tongues 74 on the tube 58 whereby the shank can be moved in or out of the tube as desired, and after the shank and tube have been positioned at the desired location relative to each other, the heel member 31 and sole member 32 can be turned slightly so as to cause the tongues 74 to be moved out of registry with the channels 63 whereby no further longitudinal relative movement between the shank and tube can take place. When the lugs or tongues 74 move out of engagement with the channels 63, the tongues will move into engagement with the grooves 62 between the ribs 60.

In FIGURE 4 the parts are shown in locked position so that no further lengthwise adjustment of the skates can occur, while in FIGURE 5 the parts are shown in a different position wherein the tongues 74 are in registry with the channels 63 so that with the parts in the position of FIGURE 5 the length of the skates can be varied or regulated as desired. In FIGURE 8 the tongues 74 are in registry with the channels 63 so that the mechanism 57 is in unlocked position whereby the length of the skates can be changed or varied, while in FIGURE 9 the

tongues 74 are out of registry with the channels 63 so that the skates will be locked.

The ribs 60 are adapted to be provided with outer flattened surfaces 62, and the tube 58 has inner flattened surfaces 76 so that for example as shown in FIGURE 8 when the flat surfaces 61 and 76 are contiguous to each other there will be no camming or wedging action, while when the parts are in the position of FIGURE 9, outer edge portions of the ribs 60 will snugly engage the flat surfaces 76 so as to exert a holding or wedging action which will help prevent the shank from accidentally rotating or turning from its locked position. However, this holding action can be overcome by the child applying manual pressure to the parts such as the members 31 and 32 so that the lengthwise adjustment of the skates can take place when desired. In effect by providing the slightly flattened surfaces 61 on the shank 56, it will be seen that the distance between the pair of flat surfaces or sections 61 will be slightly less than the distance or length between points spaced 90° from the flat surfaces 61 so that when the flat surfaces 61 are contiguous to the flattened shoulders 76, there will be no wedging action, but when the shank 56 is turned a quarter turn or approximately ninety degrees, the flat surfaces 61 will be moved away from the flat shoulders 76 so that the high points on the shank 56 will engage the flat shoulders 76 to exert the previously described camming or holding action.

The notched or toothed portion 47 of the strap 46 is adapted to engage the openings 48 and 49 whereby the strap can be maintained in its desired position.

The shank 56 is rigidly affixed to or formed integral with the end portions 50, and the braces 53, 54 and 55 are arranged in such a manner that the shank will be supported in the necessary horizontal position whereby the proper alignment can be maintained or insured between the shank and tube of the locking mechanism. Similarly the tube 58 is firmly affixed to the various parts of the sole member 32 as previously stated so that the tube 58 will likewise be properly held in the correct position for coaction with the shank of the heel member 31.

The parts can be made of any suitable material and in different shapes or sizes.

An important aspect or feature of the present invention is the unique adjustable locking mechanism as previously described. With the present invention a small child can properly position the parts so as to adjust the length as desired, and it is only necessary to move the sole member and heel member relative to each other by a twisting action so that the tongues are in registry with the channels, and then the members can be adjusted to the desired length whereby afterwards the heel member and sole member can be returned to their normal position so that the base portion 33 and base piece 65 are co-planar whereby the skate will be in the desired locked position. The upper surfaces of the base portion 33 and base piece 65 are adapted to be roughened so as to help prevent slippage between the child's shoe and these parts, and this roughened surface is indicated generally by the numeral 79 in FIGURE 11. The locking mechanism is constructed so that the parts can be readily and easily adjusted even by a small child, and the skates can be made inexpensively by utilizing plastic materials for the various parts. In addition the skate incorporates the safety features as previously stated such as the safety brake which includes the flanged section 37. When the heel member and toe member are aligned they will be locked, as for example when the parts are in the position shown in FIGURE 2.

It is to be noted that according to the present invention there has been provided an improved roller skate which differs from prior roller skates by including or embodying a different strap, and wherein there is provided a different locking mechanism which includes the straight spaced parallel grooves, as for example as shown in FIG-

URE 6, and wherein the back portion of the skate is different as for example as shown in the left side portions of FIGURES 2 and 3 of the drawings, and the skate embodies or utilizes wheels which are small in diameter, and also it is to be noted that the toe piece 66 is of a generally closed construction at its front portion, and the toe piece 66 is provided with the projection or enlargement 78 thereon, and this construction of the toe piece insures that there will be a better fit of the child's shoe in the skate.

10 Minor changes in shape, size and rearrangement of details coming within the field of invention claimed may be resorted to in actual practice, if desired.

What is claimed is:

15 1. In a roller skate, a heel member and a sole member, means adjustably connecting said heel member and sole member together, said means embodying a hollow tube affixed to one of said members and said tube being provided with a pair of inwardly disposed diametrically opposed tongues, a shank affixed to the other of said members, and said shank being provided with diametrically opposed spaced apart channels for selectively receiving therein said tongues, an external portion of said shank having two groups of arcuate ribs, adjacent ribs defining therebetween grooves for selectively receiving therein said tongues, said two groups of the ribs being separated by said channels, said tube being provided with inwardly disposed shoulders which are provided with flattened surfaces, and said ribs having flat surfaces mounted for movement into and out of a position contiguous to the flattened surfaces of said shoulders.

20 2. In a roller skate, a heel member and a sole member, means adjustably connecting said heel member and sole member together, said means embodying a hollow tube affixed to one of said members and said tube being provided with a pair of inwardly disposed diametrically opposed tongues, a shank affixed to the other of said members, and said shank being provided with diametrically opposed spaced apart channels for selectively receiving therein said tongues, an external portion of said shank having two groups of arcuate ribs, adjacent ribs defining therebetween grooves for selectively receiving therein said tongues, said two groups of ribs being separated by said channels, said tube being provided with spaced apart diametrically opposed shoulders that have flat surfaces thereon, and said ribs having flat surfaces mounted for movement into and out of a position contiguous to the flat surfaces of the shoulders, the tongues of the tube being interposed between the shoulders of the tube, said channels having their longitudinal axes arranged at right angles with respect to the longitudinal axes of the grooves.

25 3. In a roller skate, a heel member and a sole member, said heel member including a horizontally disposed base portion, a V-shaped cradle depending from said heel member, a horizontally disposed rear axle mounted in said cradle, rear wheels connected to the ends of said axle, a flanged section depending from said heel member and said flanged section having its lower end terminating at a point just above the lower periphery of the rear wheels, said flanged section including spaced apart side portions which are cut away to provide clearance for the rear wheels, the side portions further embodying upper skirt portions, said flanged section further including a rear portion provided with an arcuate recess, apertured brackets extending upwardly from the rear of the heel member, a strap extending through said apertured brackets, a vertically disposed end portion depending from the front of the heel member, said end portion including an intermediate enlarged rounded section and upper portions of reduced size, vertically disposed spaced parallel brace pieces extending between said cradle and the rounded section and affixed thereto, inclined brace members extending between said brace pieces and said skirt portions, spaced apart brace elements extending between said brace members and end portion and secured thereto, a hori-

zontally disposed hollow shank affixed to the intermediate enlarged rounded section of said end portion, said shank having on its exterior two groups of spaced apart arcuate ribs, there being grooves defined between adjacent ribs, the ends of the ribs being separated from each other by diametrically opposed longitudinally extending channels, said ribs having flattened outer surfaces thereon, said shank further including a smooth outer end portion free of ribs, said hole member further including a horizontally disposed base piece having an upstanding generally closed toe piece adjacent the front thereof, a pair of spaced apart side members depending from said base piece and said side members including enlarged generally triangular shaped sections which are joined at their lower surfaces by an arcuate crosspiece, a front axle extending between said triangular shaped sections and arranged above said crosspiece, front wheels journaled on the ends of said front axle, a horizontally disposed open ended tube for adjustably receiving therein said shank, and said tube having a portion thereof affixed to the lower surface of said base piece, said tube being also affixed to said crosspiece, a horizontally disposed brace extending between said triangular sections and affixed thereto, said last named brace being also affixed to said tube, diametrically opposed arms positioned above said last named brace and

said arms extending between said triangular sections and tube and secured thereto, a pair of diametrically opposed tongues projecting inwardly from an end of said tube for selectively engaging the grooves and channels of the shank, the interior of the tube being provided with diametrically opposed thickened shoulders having flat surfaces, the flat surfaces of the ribs being mounted for movement towards and away from the flat surfaces of the shoulders.
